FEELER MECHANISM FOR LOOMS

Application filed September 13, 1928. Serial No. 305,635.

This invention relates to feeler mechanisms for looms whereby the operative condition of the loom is changed from time to time as the filling becomes substantially exhausted. The change in the operative condition of the loom is usually one that effects filling replenishment, and the present invention will be described in this connection.

Several types of feeler mechanisms have been suggested heretofore in an attempt to minimize waste of filling upon replenishment of filling in the shuttle and among such feeler mechanisms is that commonly known as the "side slipping" feeler, wherein the feeler moves longitudinally of the shuttle when the filling is substantially exhausted on a detecting beat. Such side slipping movement of the feeler is imparted either by the frontward pressure of a surface within the shuttle or by means such as a spring which acts upon the feeler independently to cause its side slipping movement. The present invention is more particularly directed to a feeler mechanism of the side slipping type wherein the feeler is spring stressed to effect its indicating or side slipping movement.

Waste filling, of course, depends upon the amount of yarn left upon the filling carrier when it is ejected from the shuttle on replenishment of filling and the problem presented to a feeler mechanism to minimize such waste is a delicate one and depends largely upon the accuracy and delicacy of the feeler operation. One of the objects of the present invention is to provide a feeler mechanism of the side slipping type which shall be under the influence of a spring so constructed and related to the feeler itself that it will act both to impart to the feeler its rearward movement into filling feeler position and upon frontward movement the stress of the spring may be exerted to impart to the feeler a tendency to move longitudinally of the shuttle.

More specifically stated, the present invention provides a floating, side slipping feeler,

having a laterally extending arm and a fulcrum stop against which the feeler is held by a spring acting in an inclined direction and exerting its stress on a line rearward of the fulcrum stop when the feeler is in feeling position, and frontward of the fulcrum stop when the feeler is moved frontwardly, the result being that the single spring acts both to position the feeler for its feeling function and then acts when the feeler is moved frontwardly to impart a tendency to its side slipping movement.

The invention and novel features thereof will best be made clear from the following description and the accompanying drawings of one good form of the invention.

In the drawings:

Fig. 1 is a perspective view with parts broken away showing sufficient of the loom and feeler mechanism to make clear the operative condition of the latter;

Fig. 2 is a plan view showing the action of the feeler mechanism on a detecting beat when a working supply of filling is present in the shuttle;

Fig. 3 is a plan view showing by full lines the position of parts on a detecting beat when the filling is substantially exhausted, and by dotted lines the relation of parts when the feeler is in its rearward feeling position; and

Fig. 4 is a section on the line 4—4 of Fig. 3.

As hereinbefore indicated, feeler mechanisms are now generally employed in looms to effect replenishment of filling when that in the active shuttle has become substantially exhausted, but since the replenishing mechanism and its manner of operation are both now well understood in the art such mechanism is not here shown as its details form no part of the present invention.

The shuttle box 1 may be of usual construction and the front wall thereof may have an opening for the entrance of the feeler as is now the ordinary practice. The shuttle 2 con-

tains the filling carrier 3, the head portion 4 of which is provided with rings 5 for engagement with the usual bobbin holding jaws of the shuttle, and the front wall of the shuttle is provided with an opening 6 through which the feeler may pass and detect the condition of the filling, all as usual.

Mounted upon the loom frame or shipper stand is a bracket 7 upon which is secured the feeler stand 8 by means of a bolt 9 which is passed through an opening 10 in the feeler stand. The feeler 11 is mounted directly on the feeler stand for movement towards and from the front of the loom and longitudinally of the shuttle. The rear end portion of the floating feeler 11 is provided with one or more teeth 12 which are adapted to engage the filling in the shuttle and prevent side slipping movement of the feeler when a working supply is present on a detecting beat.

The feeler 11 extends through an opening 13 formed in an upstanding flange or rib 14 at the rear of the feeler stand and has liberty of movement towards and from the front of the loom and longitudinally of the shuttle.

The front portion of the feeler 11 is provided with a laterally extending arm 15 which as shown comprises a bent portion of the front end of the feeler itself, although it may be otherwise formed. The terminal portion of the laterally extending arm 15 as shown is provided with a hook 16 to which is secured one end 17 of a pull spring 18, the rear end portion of the spring being secured to an upstanding portion 19 of the arm 20, the construction being such that the stress of the spring 18 relative to the feeler is in a rearward and lateral direction.

Mounted upon the feeler stand 8 is a pin or screw 21 which constitutes a fulcrum stop against which the main body portion of the feeler 11 rests during the loom operation and which constitutes a fulcrum about which the feeler may be turned when it is moved forwardly on a detecting beat with filling substantially exhausted. The fulcrum stop 21 may be constituted as a bolt, as indicated in Fig. 4, which, in the present instance of the invention, is passed through the inner end 22 of the arm 20 and clamped thereto by a nut 23, the construction being such that by manipulation of the nut 23 the arm 20 may be moved into different positions to change the direction of spring stress upon the feeler.

The fulcrum stop 21 may be provided with a washer 24 and an enlarged head portion 25 to maintain proper contact and position of the feeler 11.

The laterally extending arm 15 at the front portion of the feeler projects beyond the fulcrum stop, as indicated more clearly in Figs. 2 and 3, and is preferably bent rearwardly, with the result that the loop in the arm 15

embraces the feeler stop when the feeler is in its rearward feeling position.

As indicated in the present instance of the invention, the backwardly turned end portion of the arm 15 is of a length such that when the feeler 11 is in its rearward feeling position, the stress of the spring 18 will act upon the feeler along a line *a* back of the fulcrum stop, so that when the feeler is in its rearward feeling position under the action of the spring 18, the latter will exert stress upon the feeler to place it in a directly extending backward position, as indicated by the dotted lines in Fig. 3. When, however, the feeler is moved forwardly on a detecting beat by engagement either with the filling or the substantially exhausted filling carrier, the hook portion 16 of the arm 15 will likewise be moved forwardly and as the spring 18 is connected to the hook 16 the line of action or stress of the spring 18 will at such times act along the line *b* in front of the fulcrum stop, with the result that the spring stress will under these conditions tend to move the feeler in a direction longitudinally of the shuttle, as indicated by full lines in Fig. 3.

From the construction described it will be noted that the single spring acts upon the laterally extending arm 15 of the feeler at a point beyond the fulcrum stop, and when the feeler is in its rearward feeling position the line of stress exerted by the spring 18 will be back of the fulcrum stop and tend to move the feeler laterally into its proper feeling position, but when the feeler is moved forwardly on a detecting beat the line of stress of the spring will be exerted at a point in front of the fulcrum stop, as indicated in Fig. 3, thereby imparting to the feeler a tendency to move longitudinally of the shuttle. The fulcrum stop 21, therefore, constantly acts upon the feeler to guide it in its forward movement when a working supply of filling is present in the shuttle on a detecting beat, and acts as a fulcrum about which the feeler swings under the stress of the spring 18 when filling is substantially exhausted on a detecting beat.

It may be desirable at times to change the direction of the spring stress by shifting the position of the arm 20, which may readily be done by loosening the nut 23, positioning the arm 20 and then tightening the nut.

Mounted on the feeler stand 8 is a lug 26 through which extends a transmitter 27 the end portion 28 of which is in the path of movement of the feeler 11 as the latter slides along the filling carrier longitudinally of the shuttle, and associated with the transmitter 27 is a train of mechanism for effecting replenishment of filling.

What is claimed is:

1. In a feeler mechanism for looms, the combination of a feeler stand, a floating side slipping feeler mounted directly on the feeler

- stand, a fulcrum stop on the feeler stand, an arm extending laterally from the feeler and having a rearwardly extending end embracing the fulcrum stop, and a spring connected to the end of the arm at a point beyond and rearward of the fulcrum stop when the feeler is in rearward feeling position and frontward of the fulcrum stop when the feeler is moved frontwardly that the feeler may be given its side slipping movement by the spring when the filling is substantially exhausted on a detecting beat.
2. In a feeler mechanism for looms, the combination of a feeler stand, a floating side slipping feeler mounted on the feeler stand, a fulcrum stop on the feeler stand at one side of the feeler, an arm extending laterally from the feeler and having its end portion turned rearwardly to form a loop between the feeler and the rearwardly turned portion of the arm for embracing the fulcrum stop and a spring acting on the rearwardly extended portion of the arm in a diagonal direction at the rear of the fulcrum stop when the feeler is in rearward feeling position and in a diagonal direction at the front of the fulcrum stop when the feeler is moved frontwardly that the spring may then act with a tendency to move the feeler longitudinally of the shuttle.
3. In a feeler mechanism for looms, the combination of a feeler stand, a floating side slipping feeler mounted on the feeler stand, a fulcrum stop on the feeler stand at one side of the feeler, an arm rigid with and extending laterally from the feeler and having its end portion turned rearwardly about the fulcrum stop and a pull spring acting on the rearwardly extended portion of the arm in a diagonal direction at the rear of the fulcrum stop when the feeler is in rearward feeling position and in a diagonal direction at the front of the fulcrum stop when the feeler is moved frontwardly that the spring may then act with a tendency to move the feeler longitudinally of the shuttle.
4. In a feeler mechanism for looms, the combination of a feeler stand, a floating side slipping feeler mounted directly on the feeler stand, a fulcrum stop on the feeler stand at one side of the feeler, an arm extending from the feeler and having a looped portion embracing the fulcrum stop, a spring connected to the looped portion of the arm and acting in a rearward diagonal direction back of the fulcrum stop when the feeler is in rearward position and in front of the fulcrum stop when the feeler is moved frontwardly that the spring may then tend to move the feeler longitudinally of the shuttle.
5. In a feeler mechanism for looms, the combination of a feeler stand, a floating side slipping feeler mounted on the feeler stand, a fulcrum stop on the feeler stand, an arm extending laterally from the feeler and having its end turned rearwardly forming a loop

about the fulcrum stop, a pull spring connected to the rearwardly turned end portion of the arm at a point beyond the fulcrum stop and acting laterally and rearwardly in an inclined direction to move the feeler to feeling position and exerting a stress upon the feeler when it is moved frontwardly tending to swing the feeler longitudinally of the shuttle about the fulcrum stop.

6. In a feeler mechanism for looms, the combination of a feeler stand, a floating side slipping feeler mounted on the feeler stand, a fulcrum stop on the feeler stand, an arm extending laterally from the feeler towards and beyond the fulcrum stop and having its free end portion beyond the fulcrum stop projected rearwardly about the fulcrum stop, a pull spring connected to the rearwardly extending end of the arm at a point beyond the fulcrum stop and acting rearwardly in an inclined direction to pull the feeler to feeling position and exerting a stress upon the feeler when it is moved frontwardly tending to swing the feeler longitudinally of the shuttle about the fulcrum stop, and means for changing the rearwardly inclined direction of the spring pull.

7. In a feeler mechanism for looms, the combination of a feeler stand, a floating side slipping feeler mounted directly on the feeler stand, a fulcrum stop on the feeler stand at one side of the feeler, an arm extending laterally from the feeler beyond the fulcrum stop and having the end portion turned rearwardly to form a loop about the fulcrum stop, and a spring connected to the end portion of the arm beyond the fulcrum stop and acting to move the feeler to feeling position and to exert stress upon the feeler tending to move it longitudinally of the shuttle about the fulcrum stop when the feeler is moved frontwardly.

8. In a feeler mechanism for looms, the combination of a feeler stand, a fulcrum stop mounted on the feeler stand, a floating side slipping feeler mounted on the feeler stand and having its front portion extended laterally past the fulcrum stop and there turned rearwardly, an arm secured to the feeler stand, a spring having its rear end connected to the arm and its opposite end secured to the rearwardly turned end of the front portion of the feeler at a point beyond the fulcrum stop and acting in a rearwardly inclined direction back of the fulcrum stop when the feeler is in rearward feeling position and in front of the fulcrum stop when the feeler is moved frontwardly on a detecting beat.

9. In a feeler mechanism for looms, the combination of a feeler stand, a feeler to feel for the filling in the shuttle on detecting beats and mounted for movement towards and from the front of the loom and in a direction longitudinally of the shuttle, a fulcrum pivot about which the feeler swings when it moves longi-

tudinally of the shuttle and a pull spring for moving the feeler to its rearward feeling position and pulling laterally on the feeler rearward of the fulcrum pivot when the feeler is in rearward feeling position and frontward of the fulcrum pivot when the feeler is moved frontwardly on a detecting beat to impart a tendency for the feeler to side slip.

5 In testimony whereof, I have signed my name to this specification.
